UNITED STATES PATENT OFFICE

MAURICE FRANK HUTCHISON, DECEASED, LATE OF HERNDON, VIRGINIA, BY CLARE E. HUTCHISON, ADMINISTRATRIX, OF HERNDON, VIRGINIA

DRAFT REGULATOR

Application filed March 17, 1928. Serial No. 262,404.

This invention has for its object the provision of a novel form of draft-regulator for use in a steam heating system whereby the draft through the furnace will be cut off or opened automatically as the pressure in the system rises or falls.

One particular object of the invention is to provide novel mechanism whereby the dampers will be held closed until a predetermined degree of vacuum has been established in the system and will then be opened and held open until predetermined pressure has been established.

A preferred form of the invention is illustrated in the accompanying drawing and hereinafter fully set forth and more particularly defined in the appended claims.

In the drawing:

Fig. 1 is an elevation of a device embodying the invention;

Fig. 2 is a top plan view of the same;

Fig. 3 is a detail elevation, viewing the side opposite that seen in Fig. 1.

In carrying out the invention, there is provided a casing 1 containing a bellows or flexible diaphragm (not shown) of well-known construction. This casing is provided with securing screws 2 in lugs 3, whereby the casing may be secured in level position upon a furnace, and it is further provided with a central nipple 4 on its bottom to be coupled into the boiler of the furnace and establish communication with the steam space thereof so that the diaphragm or bellows will be subjected to the steam pressure. Rising from the bellows and extending through the top of the casing is a post 5, and secured to said post is the member 6 having its upper end forked to span a lever 7 which is constructed at one end with a yoke or bridge 8 and at said end is pivoted upon a fulcrum post or lug 9 formed on the top of the casing and fitting within an opening provided therefor in the lever.

A damper-actuating bar, indicated by the dotted lines 10, is inserted through the yoke 8 and secured by a set screw 11 which clamps it in notched lugs 12 on the upper side of the lever, said bar being connected with the fur-

nace dampers by chains as is common practice.

The free end of the lever 7 is formed into a fork 13 to accommodate two dogs or holding bars 14 and 15 which are pivoted at their lower ends to a lug 16 on the casing and have their upper ends disposed at opposite sides of the damper-actuating bar, and a pin 17 fitted transversely through the lever at the base of the fork is arranged to ride on the inner edges 55 of the dogs and engage notches therein. 60

The notch 18 in the dog 15 is located near the upper end thereof while the notch 19 in the dog 14 is located near the lower end thereof. The stop shoulder or pin-engaging wall 65 of each notch is disposed obliquely with respect to the edge of the dog but the shoulder is at the upper end of the notch 19 and at the lower end of the notch 18. Attached to the respective dogs are retractile springs 20, 21, 70 which extend across the casing and have their opposite ends attached to anchoring screws 22 which are mounted in lugs 23 on the casing and are adjustable therein to regulate the tension of the springs. 75

The latch is indicated at 24 which may be caused to bear against the side of the casing and thereby hold the dogs 14 and 15 inoperative.

In the position shown in Fig. 1, the pressure of the steam in the boiler is pushing the post 5 and yoke 6 upward, and the free end of the lever 7 is swinging upward, a corresponding movement being imparted to the damper-actuating bar. When the described 80 travel of the pin 17 brings it to the notch 18, the spring 21 at once contracts and rocks the dog 15 to effect engagement between the pin and the notch and the movement is so timed that the dampers will be closed when the pin 85 enters the notch 18. The spring 21 having been adjusted to degree of vacuum desired in the heating system, the parts will be held in the position in which they are now set until the reduction of pressure in the system produces the predetermined degree of vacuum whereupon the resulting suction will tend to draw the lever 7 downward, releasing the pin 17 from the notch 18. The downward rocking 90 of the lever 7 will effect opening of the damp- 95

ers and will continue until the pin 17 engages the notch 19 which will hold the parts until the pressure of the steam overcomes the tension of the spring 20 whereupon the cycle of operation will be repeated.

5 The device is exceedingly simple and compact and may be easily applied to any furnace at a slight cost. After being installed it needs no attention and operates automatically and 10 efficiently to cut off the draft when the generated steam attains a predetermined pressure and to open the draft when the vacuum due to reduction of the pressure reaches a pre-determined degree.

15 Having thus described my invention, what I claim as new and desire to secure by Letters Patent of the United States, is:—

20 1. In a draft-regulator, a pressure-responsive damper-actuating lever, a pair of dogs arranged adjacent the free end of the lever and adapted one to engage the lever at the upper limit of its movement and one to engage it at the lower limit of its movement, and springs attached to the respective dogs to effect engagement of the same with the lever, the tension of the springs being respectively set to hold the lever raised against the influence of a pre-determined degree of vacuum and lowered against the influence of a pre-determined pressure.

25 2. In a draft-regulator, a damper-actuating lever fulcrumed at one end and having a fork at its free end, a pressure-responsive post bearing against the under side of the lever between the ends thereof, a pair of dogs passing through the fork of the lever and fulcrumed at their lower ends below the lever, one of said dogs having a notch in its inner edge near its upper end and the other dog 30 having a notch in its inner edge near its lower end, a pin in the lever at the base of the fork, and means for rocking the respective levers to effect engagement between the pin and the notch presented thereto.

35 45 Signed at Herndon, Virginia, this 6th day of March, 1928.

CLARE E. HUTCHISON.
